OVERVOLTAGE PROTECTOR

Robert L. Brown, Teaneck, N. J., assignor to Bendix Aviation Corporation, Teterboro, N. J., a corporation of Delaware

Original application October 15, 1947, Serial No. 779,992. Divided and this application October 5, 1949, Serial No. 119,724

4 Claims. (Cl. 171—119)

1

This application is a division of Application Serial No. 779,992, filed October 15, 1947, and relates to overvoltage protection for electrical generator systems and more particularly to improvements in the system and protector of the type shown in the copending application for U. S. Patent Serial No. 701,322, filed October 4, 1946, now Patent No. 2,522,601, issued September 19, 1950, by Robert Lowell Brown.

An object of the invention is to provide overvoltage protection which does not respond to sudden surges of short duration of overvoltage.

It is desirable in the event of an overvoltage on one generator of a parallel arrangement that the other protectors do not trip due to surges caused by the finite time of operation of the faulted protector, reverse current relays, regulators and line switches. While the regulators of the normally functioning generators will automatically tend to keep the non-faulted protectors from tripping after a short, an object of the invention is to provide means for effecting an immediately acting time delay (of short duration) to keep the protectors from tripping before the regulators can take over.

Another object of the invention is to provide an immediately acting time delay (of short duration) for the protectors which is introduced by the use of short circuiting slugs (rings) of copper arranged concentric with the coil on the electromagnet. Thus with the time delay in the protectors plus the correcting action of the regulators the non-faulted protectors will not trip when a parallel system is disturbed by an overvoltage generator.

The above and other objects and features of the invention will appear more fully hereinafter from a consideration of the following description taken in connection with the accompanying drawings wherein one embodiment of the invention is illustrated by way of example.

In the drawings the single figure is a diagrammatic representation of a generator system embodying the invention.

The purpose of the overvoltage protector device, heretofore described and claimed in the parent application, Serial No. 779,992, filed October 15, 1947, is to prevent damage to an airplane's electrical equipment when malfunctioning of a generating system causes excessively high voltage. The protector device is arranged to open the field circuit of the malfunctioning generator and in addition to effect the disconnection of its control equipment from the generator and to disconnect the generator from the main line without affecting other generating systems connected

2

in parallel to the line. Each of said generating systems are provided with a like protector device.

A typical system according to the invention in which the protector device 32 may be used is illustrated in the single figure of the drawing and may include a generator 80 having a field winding 81 and an interpole compensating winding 82. Output line 83 of the generator 80 is grounded, while output line 84 may be connected to a main bus line 85 through a line switch 86 operated by a solenoid 87.

The control equipment for the generator is indicated generally by the numeral 90 and may be of a type described and claimed in the copending application Serial No. 621,515, filed October 10, 1945, by William R. Holmes.

The control equipment 90 includes a variable resistance carbon pile 91 connected in series with the generator field 81 through a conductor 92. The field 81 is connected through conductor 93 to output line 83 and the opposite end of the carbon pile 91 may be connected to the output line 84 through a conductor 94 and the main switch contacts 55 and 56 of the protector device 32.

The variable resistance carbon pile 91 may be controlled by an adjustable armature 95 shown schematically in the drawing and which may be of a type described and claimed in U. S. Patent No. 2,427,805, granted September 23, 1947, in the name of William G. Neild and assigned to Bendix Aviation Corporation.

The armature 95 may be controlled by an electromagnetic winding 96 which may be connected across the generator output lines 83 and 84 by grounded conductor 97 and conductor 98. The conductor 98 may be connected to line 84 through switch members 44—45 of the protector device 32.

Connected across the interpole compensating winding 82 by a conductor 99 and grounded conductor 99A is a potentiometer 100 having a center tap 100A connected to a compensating winding 101 for affecting the carbon pile 91 so as to maintain a predetermined division of load between the several parallel connected generators as is explained in the aforesaid copending application Serial No. 621,515.

The opposite end of the compensating winding 101 may be connected to an equalizer line 102 through a conductor 103, relay switch 104, and switch members 44A and 45A of the protector device 32. The relay switch 104 is controlled by an electromagnetic winding 105 connected across the output lines 83—84 by grounded conductor 106 including resistance 106A, conductor 98 and switch contacts 44 and 45 of protector 32.

The relay winding 105 is controlled by a pilot

switch 107 biased by spring tension to the position shown so as to close switch contact 108. Switch 107 is connected to conductor 98 while contact 108 is connected to conductor 106 so that upon switch 107 closing contact 108, relay winding 105 is shunted out of operation.

The pilot switch 107 is controlled by an electromagnetic winding 109 connected through conductor 98 and switch contacts 44-45 of the protector device to output line 84 and through 10 grounded conductor 110 to output line 83.

Upon the output generator voltage rising above a predetermined value the relay switch arm 107 is biased by relay 109 so as to open contact 108 and close a contact 111. The latter action opens 15 the shunt circuit of relay winding 105 causing the winding 105 to close switch 104 whereupon the compensating winding 101 is connected into operation and to the equalizer line 102.

Moreover upon relay switch 107 closing contact 111 a current winding 112 is connected across the open line switch 96 by a conductive passage leading from line 84 through switch contacts 44-45 of the protective device 32, conductor 98, switch 107, contact 111, current winding 112, and a conductor 113 to the main bus line 85. The winding 112 is wound about a permanent magnet 114 and is arranged to cooperate therewith so that upon a current flow from the generator 80 to the main bus line 85 the magnetic effect of coil 112 and permanent magnet 114 will exert an additive effect biasing a relay switch 115 to close contact 116.

The relay switch 115 is connected by a conductor 117 to conductor 94 and through switch contacts 55 and 56 to the output line 84. The contact 116 is connected by conductor 118 through the switch contacts 46-47 of the protector device 32 to the line relay 87. The closing of switch 115 will then cause energization of the line relay 87 and the closing of the line switch 86 which will shunt differential current winding 112 out of operation.

Cooperating with the winding 112 is a second current winding 120 connected across the interpole compensating winding 82 through conductor 121 and grounded conductor 122. So long as the current flow is from the generator 80 to the main line 85 the winding 120 will exert an additive effect with the permanent magnet 114 tending to hold the control switch 115 closed. However, in the event the output of the generator 80 decreases to such a point that the current output of the generator is below that of the main bus line 85, then the winding 120 will exert a differential effect with the permanent magnet 114 tending to decrease the magnetic effect acting on the relay switch 115 so that the switch 115 under spring force is biased to a position opening contact 116. The latter action deenergizes the winding 87 causing line switch 86 to open.

As shown schematically in the drawing, switch contacts 46-47, 44-55, 55-56, 44A-45A, and 46A-47A may be closed by manually actuating the push rod 24. The same may be latched in the latter position through action of the latch mechanism 21 as heretofore explained.

The closing of switch contacts 46A-47A connects a sensing coil, the electromagnetic winding 10, across the field 81 of the generator 80 through conductors 130 and 131.

When the voltage across the field 81 reaches a predetermined excessive value for any reason, the sensing coil 10 actuates the armature 15 and through the studs 35 the latch 21, thus releasing 75

the reset rod 24 and opening the main contacts 55-56, and the four pairs of auxiliary contacts 46-47, 44-45, 44A-45A, and 46A-47A.

In the latter event the following action takes effect. The contacts 46-47 open the potential circuit for the line relay 87 and thereby cause line switch 86 to open and effect deenergization of current winding 120. The contacts 44-45 open the potential circuits for the carbon pile voltage coil 96, relay voltage coil 105, and relay voltage coil 109. Deenergization of coil 109 causes in turn relay switch 107 to open contact 111 and thereby the circuit to differential current coil 112. The main contacts 55-56 open the generator field circuit. The auxiliary contacts 44A and 45A open the circuit of the compensating winding 101. The auxiliary contacts 46A and 47A open the circuit of the sensing coil 10.

As an alternative arrangement the switch 20 44A-45A may be normally open so that upon the latch 21 releasing the reset rod 24 the switch 44A-45A may close a circuit to energize a warning device such as an electric light or bell to indicate that the overvoltage protector has disconnected one generating system from the main bus.

As shown diagrammatically in the drawing, a plurality of generators 80, 80A, 80B and 80C may be parallel connected to the main bus line 85. 30 Each of the generators 80A, 80B and 80C has similar control equipment to that indicated generally by numeral 90 and indicated herein as 90A, 90B and 90C, respectively. Likewise the generators 80A, 80B and 80C have protector devices similar to the protector device 32 of the generator 80 and indicated herein as 32A, 32B and 32C, respectively.

Surge voltages due for example to a faulted generator will not actuate the overvoltage protector of the other non-faulted generators. This condition is achieved by the incorporation of the copper washers 71, which act as shorted turns on the sensing coil 10. Such shorted turns in an inductive system generate flux that opposes the flux generated by the coil 10. Thus during 45 change in the energizing current of the coil 10 this opposition retards the build-up of sufficient coil flux to actuate the armature 15, so as to provide a sufficient time lag to prevent tripping of the latch 21 by surge voltages. This time lag is further insured by the construction of the armature 15 and latch 21. The armature 15 has studs 35 arranged to trip the latch 21 after the armature has traveled about two-thirds of its distance 50 to the electromagnet 10. This construction also permits the tripping voltage to be unaffected by friction.

Once the overvoltage protector has operated the reset rod 24 may be pushed down to reset the mechanism by manually compressing the bellows 34.

Although only one embodiment of the invention has been illustrated and described, various changes in the form and relative arrangements of the parts may be made to suit requirements.

What is claimed is:

1. In combination, an output line, a plurality of generators connected to said output line, each of said generators having a field circuit, control means responsive to the current flow through the field of each generator for disconnecting the associated generator from the output line upon a rise in field current above a predetermined value, and time delay means for retarding operation of said control means upon a voltage surge in ex-

cess of a predetermined value affecting the control means.

2. The combination defined by claim 1 in which said control means includes an electromagnetic winding and relay switch means operated thereby and associated with each of said generators; and said time delay means includes a short circuited turn about said winding and so arranged as to retard disconnection of the associated generator upon a transitory voltage surge affecting said winding.

3. In combination, a main output line, a plurality of generators, each of said generators having a field circuit, an output voltage regulator and a reverse current relay means to control the connection of the associated generator to the main output line; the improvement comprising an overvoltage protective relay means associated with each generator and arranged to effect the

disconnection of said main output line, field circuit, voltage regulator, reverse current relay means, and overvoltage protective relay means from its associated generator upon an excessive current flow through said circuit.

4. The combination defined by claim 3 including a time delay means associated with each overvoltage protective relay means to retard operation of said relay means upon a transitory excessive current flow through said field winding.
